UNITED STATES PATENT OFFICE

WERNER M. LAUTER, OF BROOKLYN, NEW YORK, ASSIGNOR TO E. R. SQUIBB & SONS,
OF NEW YORK, N. Y., A CORPORATION OF NEW YORK

ANALGEO-HYPNOTIC COMPOSITION

No Drawing.

Application filed May 19, 1928. Serial No. 279,211.

My invention relates to analgeso-hypnotic compositions and particularly to molecular compounds of amidopyrin, i. e. 1-phenyl-2,3-dimethyl-4-dimethylamino-5-pyrazolon, and derivatives of barbituric acid, i. e.

wherein X¹, X², X³, and X⁴ represent hydrogen or substituents therefor.

Such compounds are valuable medicinal agents because of their soporific power in the presence of pain. They are made by mixing the ingredients (preferably having first dissolved them in a common solvent and evaporated the latter), melting the mixture, maintaining it above fusion temperature for a short while, and then cooling.

As heretofore produced, however, these compounds have been characterized by a yellow color and an offensive odor.

It is the object of my invention to provide molecular compounds of this type that shall be substantially white and inodorous.

I have found that this object may be achieved by conducting the steps in the preparation of these compounds anaerically, that is to say, in an inert atmosphere.

For example, the following process, if performed in an atmosphere of carbon dioxide, will yield a substantially white and inodorous molecular compound: 53.85 grams of amidopyrin and 46.15 grams of ethylisopropylbarbituric acid are dissolved in 200 cc. of acetone, the latter is evaporated off, and the residue is fused, maintained at about 98° C. for fifteen minutes, cooled, and powdered.

It will be understood that various changes may be made within the scope of the appended claims without departing from my invention or sacrificing any of the advantages thereof.

I claim:

1. A substantially white and inodorous molecular compound of amidopyrin and ethylisopropylbarbituric acid.

50 2. The process which comprises causing

amidopyrin to react with ethylisopropylbarbituric acid in an inert atmosphere.

3. The process which comprises causing amidopyrin to react with ethylisopropylbarbituric acid in an atmosphere of carbon dioxide.

4. The process which comprises dissolving amidopyrin and ethylisopropylbarbituric acid in acetone, evaporating to dryness, heating the residue above its melting point for a short time, and cooling, all the operations being performed in an atmosphere of carbon dioxide.

5. The process which comprises dissolving amidopyrin and ethylisopropylbarbituric acid in acetone, evaporating to dryness, heating the residue above its melting point for a short time, and cooling, all the operations being performed in an inert atmosphere.

In testimony whereof I affix my signature.

70 WERNER M. LAUTER.
